(57) **CLAIM**

We claim the ornamental design for an automobile vehicle striker assembly, as shown and described.

DESCRIPTION

FIG. 1 is a perspective view of an automobile vehicle striker assembly showing our new design;

FIG. 2 is a left side elevational view thereof, the right side elevational being a mirror image thereof;

FIG. 3 is a top plan view thereof;

FIG. 4 is a front elevational view thereof;

FIG. 5 is a rear elevational view thereof; and,

FIG. 6 is a bottom plan view thereof.

The broken lines are for illustrative purpose only and form no part of the claimed design.
